UNITED STATES PATENT OFFICE.

JOHN FRANCIS TINER, OF UVALDE, TEXAS, ASSIGNOR OF ONE-HALF TO WILLIAM A. TIMBERLAKE, OF UVALDE, TEXAS.

FLYING-MACHINE.

1,105,941.

Specification of Letters Patent. Patented Aug. 4, 1914.

Application filed February 21, 1913. Serial No. 749,943.

To all whom it may concern:

Be it known that I, JOHN F. TINER, a citizen of the United States, residing at Uvalde, in the county of Uvalde and State 5 of Texas, have invented a new and useful Flying-Machine, of which the following is a specification.

This invention has reference to improvements in flying machines of the aeroplane 10 type, and its object is to provide for the more efficient utilization of artificially produced air currents than is the case with propelling means of the type commonly employed.

15 In accordance with the present invention there is provided a suitable frame with a motor, aeroplanes, and rudder and dip planes, while the propelling means are in the form of elongated rotatable cylinders 20 inclosing helical blades each of an axial extent substantially that of the cylinder, and, moreover, the cylinders may be as long or even longer than the body of the machine.

By the employment of the axially elongated 25 propellers the moving air currents are more compact and are directed with greater force against the relatively still air than is the case with the ordinary propellers, which latter cause the air to spread rapidly away 30 from the axis of rotation of the propeller, whereby a material part of the propelling effort is so diffused as to be practically lost.

The invention will be best understood 35 from a consideration of the following detailed description taken in connection with the accompanying drawings, forming a part of this specification, with the further understanding that while the drawings show a practical embodiment of the invention, the 40 latter is not confined to any strict conformity with the showing of the drawings, but may be changed and modified so long as such changes and modifications mark no material departure from the salient features 45 of the invention.

In the drawings:—Figure 1 is a plan view 50 of a flying machine embodying the present invention. Fig. 2 is a longitudinal and substantially vertical section through the improved flying machine. Fig. 3 is a front elevation of the improved flying machine. Fig. 4 is a longitudinal diametric section 55 through a portion of one of the propellers showing the blades partly in elevation and partly broken away, and drawn on a larger

scale than the preceding figures. Fig. 5 is a fragmentary section on the line 5—5 of Fig. 3 but drawn on a larger scale.

Referring to the drawings, there is shown a main frame made up of longitudinal members 1, cross members 2 and uprights 3 with other cross members 4 near the front and rear of the frame, and at a distance above the main body of the frame, while brace rods 5 are employed wherever necessary, 65 only a few of such brace rods being indicated in the drawing to avoid confusion of illustration. It is customary to mount aeroplanes upon wheels and consequently the body of the aeroplane of the present invention is shown as provided with wheels 6, which, however, need no specific description.

To the rear of the main frame are other frame members 7, 8, 9, contracting toward the rear where there is mounted a rudder 10 75 of suitably braced framework covered with fabric or otherwise constructed in accordance with aeroplane practice.

In the rear frame of the machine and mounted upon a transverse rod 11 is a 80 dip plane 12.

The rudder has a post 13 with a cross arm 14 from which lead ropes or strands 15 to a manipulating lever 16 mounted upon the lower beams 1 of the main frame, which beams are of sufficient strength to support an engine 17 and a seat 18 for an operator, as well as such mechanisms as are usually provided. The dip plane 12 has a cross bar 19 fast to it on opposite sides of the pivot 90 or hinge rod 11 and ropes or strands 20 lead therefrom to a manipulating lever 21 within reach of the operator.

No attempt is made in the drawings to show any particular type of motor 17, but 95 it is customary to provide flying machines with explosion motors, and the motor 17 may be taken as typical of any suitable type of explosion engine of which numerous types are obtainable for the propulsion of 100 flying machines.

The upper portion of the main frame has its cross beams 2 laterally elongated, and these beams support bowed members 22, 23, 105 which because of their functions may be designated planes, although they are bowed instead of being flat. The planes 22, 23 are continued rearwardly beyond the back end of the main frame to the upright 9 carrying the dip plane 12, but the side planes 23 are 110

narrowed progressively toward the rear until they merge into the central plane. These specific features, however, may be varied more or less as may be found expedient 5 in practice.

The top cross beams 4 carry near their ends supports 24 in which are mounted rods 25, each rod extending from one support 24 to the other.

10 Upon each rod 25 there is mounted a hollow shaft 26 by means of anti-friction bearings 27 at each end, and each end of each shaft 26 carries a pulley 28 between which and the adjacent support 24 there may be 15 provided anti-friction thrust bearings 29.

Secured to each shaft 26 on its exterior is a circular series of helical blades 30, there being four such blades shown in the drawings, and each series of blades is inclosed in 20 a cylindrical casing 31, open at the ends. The length of the blades with respect to their pitch is such that each blade includes somewhat less than a full turn about the axis of rotation of the shaft 26 and need 25 not exceed two hundred and seventy degrees. It is to be understood, however, that the invention is not of necessity limited to any particular pitch of the blades, but it is of moment that the blades shall each have an 30 appropriate pitch and shall be inclosed in a cylindrical casing of considerable length.

Hollow or tubular rods 32, 33, respectively, extend from near the outer ends of the cross pieces 4 to the lower portion or 35 flooring beams 1 adjacent the main shaft 34 of the motor 17, which shaft carries pulleys 35 at the ends for driving belts 36 extending through the tubular rods 32, 33, respectively, to the respective pulleys 28. Since the 40 blades 30 are reversely arranged within the two cylinders 31 it is necessary to drive one shaft 26 in one direction and the other in the opposite direction, wherefore one set of tubular rods, say, the rods 33, are crossed 45 and the corresponding belts 36 are likewise crossed, so that the motor may be run constantly in one direction but give reverse directions of rotation to the cylindrical fans or propellers. Where the tubular rods 33 50 cross there is mounted a grooved pulley 37 designed to hold the crossed belt 36 where crossing out of contact to prevent wear.

Suppose, now, that the aeroplane is resting on the ground upon the wheels 6 and 55 that the engine is running. By means of the usual controlling devices the engine shaft is coupled up to the pulleys 35 and rotative movement in the proper direction is imparted to the cylindrical propellers 60 which may be generally referred to as the propellers 31, this being the numeral indicating the casing of the propellers. Air is drawn into the front ends of the casing and is forced through the same by the blades 30, 65 escaping in a relatively solid and more or

less compressed column from the rear end of the casing, this expulsion of the air being with great force and is projected at a considerable distance before the air can expand and lose its compactness. The result of 70 this is that a strong propulsive effort is exerted tending to push the machine forwardly on its wheels, and this forward impulse is added to by the suction effort at the front ends of the casings. By appropriately adjusting the dip plane 12 the front end of the vehicle is caused to rise, so that the planes 22 and 23 are presented to the air in a manner which tends to lift the entire structure in accordance with the actions of other 80 aeroplanes or flying machines of like type.

The action of the flying machine of the present invention is in general similar to that of well known types of flying machines, but the propelling force is greatly increased 85 because of the great elongation of the blades of the propellers and the incasing of these blades to confine the air passing through them until great speed of the air may be attained and the air be correspondingly compacted, so that it shall issue from the propellers in the form of streams which do not immediately expand, but because of their velocity will travel an appreciable distance from the discharge end of the cylindrical 90 casings of the propellers before it begins to expand to an extent to materially cut down its efficiency. This means a propulsive effort far in excess of that produced by an open fan, such as is customarily employed in flying 100 machines.

What is claimed is:—

1. A flying machine comprising a main or body portion with a longitudinally disposed plane with other longitudinally disposed 105 planes at the sides of the body portion and extending along corresponding edge portions of the main plane, the latter being extended rearwardly from the body portion, and the side planes tapering rearwardly to the rear 110 end of the rear extension of the main plane, and elongated tubular air propellers of substantially the same length as the body of the machine and located on opposite sides of the longitudinal center line of the machine 115 and spaced apart to substantially overlie the side planes.

2. A flying machine comprising a main or body portion with a longitudinally disposed plane with other longitudinally disposed 120 planes at the sides of the body portion and extending along corresponding edge portions of the main plane, the latter being extended rearwardly from the body portion, and the side planes tapering rearwardly to 125 the rear end of the rear extension of the main plane, and elongated tubular air propellers of substantially the same length as the body of the machine and located on opposite sides of the longitudinal center line 130

of the machine and spaced apart to substantially overlie the side planes, the machine having a rudder spaced from the rearward extension of the main plane, and a dip plane 5 between the rear extension of the main plane and the rudder and having a pivotal connection with the machine at a point below the rear extension of the main plane.

3. A flying machine provided with a main 10 or body portion having a longitudinally disposed and laterally convex main plane at the top portion, convex side planes extending from the side margins of the main plane and of substantially the same length, the 15 main plane having a rearward extension from the main frame and the side planes having tapering portions extending to the rear end of the rearward extension of the main plane, a dip plane and rudder to the 20 rear of the rearward extension of the main and side planes with the dip plane located below the uppermost portion of the main plane, and an elongated tubular air propeller of substantially the same length as 25 the main body of the machine and located above the main and side planes on opposite sides of the longitudinal center line of the machine and spaced apart to substantially overlie the side planes.

4. A flying machine provided with a body 30 frame, an aeroplane carried by the upper end of the body frame and extending beyond the rear thereof, side planes extending laterally from the main frame on a level with 35 the main plane and also extending longitudinally of the machine, the main and side planes having rearward extensions, a dip plane at the rear of the rearward extension 40 of the main plane and arranged at a lower level than the main plane, a rudder to the 45 rear of the dip plane, a power motor on the main plane below the aeroplanes, and elongated tubular air propellers above the aeroplanes on opposite sides of the longitudinal center line of the machine, said propellers 50 being of substantially the length of the main and side planes and spaced apart to have the axes of rotation over the side planes.

main plane below the aeroplanes, and elongated tubular air propellers above the aeroplanes on opposite sides of the longitudinal center line of the machine, said propellers 45 being of substantially the length of the main and side planes and spaced apart to have the axes of rotation over the side planes.

5. A flying machine provided with a body frame, an aeroplane carried by the upper 50 part of the body frame and extending beyond the rear thereof, side planes extending laterally from the main frame on a level with the main plane and also extending longitudinally of the machine, the main and 55 side planes having rearward extensions, a dip plane at the rear of the rearward extension of the main plane and arranged at a lower level than the main plane, a rudder to the 60 rear of the dip plane, a power motor on the main plane below the aeroplanes, and elongated tubular air propellers above the aeroplanes on opposite sides of the longitudinal center line of the machine, said propellers 65 being of substantially the length of the main and side planes and spaced apart to have the axes of rotation over the side planes, the propellers each comprising a cylindrical casing and helically arranged 70 blades therein to direct concentrated streams of air along opposite sides of the center line of the machine in substantially non-interfering relation with the dip plane and rudder.

In testimony that I claim the foregoing as 75 my own, I have hereto affixed my signature in the presence of two witnesses.

JOHN FRANCIS TINER.
